UNITED STATES PATENT OFFICE.

JAMES H. STOCKHAM, OF DES MOINES, IOWA.

DESIGN FOR A BADGE OR SIMILAR ARTICLE.

SPECIFICATION forming part of Design No. 33,063, dated August 14, 1900.

Application filed June 21, 1900. Serial No. 21,110. Term of patent 3½ years.

To all whom it may concern:

Be it known that I, JAMES H. STOCKHAM, a citizen of the United States of America, residing at Des Moines, county of Polk, State of Iowa, have invented and produced a certain new and useful Design for Badges and Similar Articles, of which the following is a description, reference being had to the accompanying drawings, forming a part thereof.

5 In the drawings, wherein like reference-letters indicate like or corresponding parts, Figure 1 is a plan view of a badge, showing my new design; and Fig. 2 is a sectional view taken on line 2 2 of Fig. 1.

As shown in the drawings, the leading or material feature of my design consists of a stem A of a plant or shrub bearing four leaves B C

D E, extending at an angle from one another, the whole being surmounted by a bar F, connecting two of said leaves. The general form 20 of the leaves is that of clover or shamrock, as shown. Each of the leaves, as well as the bar, is provided with a border b c d e f, respectively.

Having thus described my invention, what 25 I claim as new, and desire to secure by Letters Patent, is—

The design for a badge or similar article, as herein shown and described.

JAMES H. STOCKHAM.
